UNITED STATES PATENT OFFICE.

HERBERT E. BRIDGWATER, OF SYRACUSE, NEW YORK, ASSIGNOR TO REMINGTON TYPEWRITER COMPANY, OF ILION, NEW YORK, A CORPORATION OF NEW YORK.

TYPEWRITING MACHINE.

Application filed October 16, 1922. Serial No. 594,689.

To all whom it may concern:

Be it known that I, HERBERT E. BRIDGWATER, citizen of the United States, and resident of Syracuse, in the county of Onondaga and State of New York, have invented certain new and useful Improvements in Typewriting Machines, of which the following is a specification.

My invention relates to typewriting and like machines, and more particularly to paper feeding means for such machines.

The object of the invention, generally stated, is to provide a simple, inexpensive and highly efficient paper feed device which may be readily shifted to effective or ineffective position as may be desired, and by the mere act of thus shifting the device bringing into action means for effectively holding the device in either of such positions.

Stated more specifically, an object of the invention is to provide a simple and effective auxiliary paper feed or pressure device which may be maintained under spring pressure against the front of the platen or the paper thereon, and which, when it is desired to dispense with the use of such device, may be readily shifted to a position at a considerable distance away from the platen where it may be maintained free from interference with the work sheets.

To the above and other ends which will hereinafter appear, my invention consists in the features of construction, arrangements of parts and combinations of devices set forth in the following description and particularly pointed out in the appended claims.

In the accompanying drawings, wherein like reference characters indicate corresponding parts in the different views.

Figure 1 is a fragmentary top plan view of a portion of a typewriting machine equipped with the paper feed device of my invention.

Figure 2 is a detail fragmentary vertical fore-and-aft sectional view of the same, taken on the line 2-2 of Figure 1 and looking in the direction of the arrows at said line.

Figure 3 is a view corresponding to Figure 2 except that the paper feed device is shown in side elevation instead of in section and is shown retracted to the ineffective position.

Figure 4 is an enlarged detail transverse sectional view of the paper feed device and some of the associated parts, the section being taken on the line 4-4 of Figure 2 and looking in the direction of the arrows at 60 said line.

I have shown my invention embodied in the present instance in a Monarch typewriting machine equipped for use with Wahl adding mechanism, said machine embodying 65 inventions of Frederick A. Hart, Serial No. 630,226, filed April 6, 1923, although the paper feed device of my invention is not restricted to its use in such a machine but may be employed in various makes of typewriting or like machines.

In the accompanying drawings I have shown only so much of the machine referred to as is necessary to arrive at an understanding of my invention in its embodiment therein.

The typewriting machine comprises the usual carriage 1 supporting a platen 2. Side arms 3 are fixedly secured by suitable means to each end of the carriage. The means employed in the present instance are the same as those disclosed in the patent to Herbert H. Steele No. 1,222,694, dated April 17, 1917.

Parallel cross bars 4 have their feet 5 secured by screw bolts 6 and nuts 7 to the arms 3. These bars extend throughout the length of the carriage in front of the platen and are united at different points throughout the length thereof by shouldered spacing pins or members 8 riveted at their ends to the cross bars, as indicated at 9. As far as the present invention is concerned, these parts constitute portions of the typewriter carriage.

I utilize the cross bars 4 to support the paper feed device of my invention, although other supporting means connected to the carriage may be provided for this purpose. Arranged about centrally of the carriage is a shouldered spacing pin or member 10 which preferably is connected at its ends to the cross bars 4 by headed screws 11. The stems of these screws likewise pass through openings in foot pieces 12 of a yoke-like sheet metal bracket or support, the heads of the screws 11 firmly clamping the bracket to the cross bars. This bracket extends longitudinally fore-and-aft of the machine and the horizontally arranged top 110

or supporting portion 13 thereof is arranged above and extends fore-and-aft of the machine beyond the cross bars 4. The side edges 14 of the supporting portion 13 are 5 parallel and a centrally arranged slot 15 in the part 13 extends longitudinally thereof. A sheet metal carrier or slide, designated as a whole by the reference numeral 16, is formed at opposite sides with downwardly 10 extending inwardly bent ears or lugs 17 that embrace the sides of the supporting bracket and guide the back part of the slide in its movement on the bracket fore-and-aft of the machine, and with similarly bent ears 15 18 for the same purpose at the front end of said slide.

The ears 18, co-acting with the forward looped end 19 of the bracket limit the forward motion of the slide, as will be understood from an inspection of Fig. 3. However, the rear looped portion 19^a of the bracket is of reduced width, as indicated in Fig. 1, so that the ears 17 may pass said looped portion without arresting the rearward motion of the slide. Such motion of the slide is limited only by the co-operation of the feed device or roller carried by the slide coacting with the platen, as will hereinafter appear. The slide is preferably provided with a finger piece to facilitate its movement either to the effective position shown in Fig. 2 or to the ineffective position shown in Fig. 3. In the present instance a finger piece 20 is riveted at 21 to the slide 30 and projects upwardly therefrom where it is readily accessible to the operator. The slide is formed at its rear side edges with downwardly bent parallel supporting arms 22 which carry between their rear ends a suitable paper feed device, in the present instance in the form of a feed roller 23. This roller is journaled on a pivot pin 24 supported at its ends in openings in the arms 22 and riveted against displacement therefrom. From what has been said, it will be understood that the only appreciable movement that the slide has independently of its movement with the carriage is a movement fore-and-aft of the machine or transversely 45 of the platen from the position shown in Fig. 2 to that shown in Fig. 3, and vice versa.

In order that the slide may be retained indefinitely under spring pressure in its effective position shown in Fig. 2, or may be retained indefinitely in its retracted or ineffective position shown in Fig. 3, I provide the following means: The pin 10 has a guide slot 25 to receive an arm or controlling member 26. One end of the arm is pivoted at 27 in this slot so that the arm which extends up above its supporting member or pin 10 may swing on its pivot fore-and-aft of the machine from the position shown in Fig. 60 2 to that indicated in Fig. 3, and vice versa.

A contractile spring 28 is connected at one end to the arm 26 and at its other end to a pin 29 riveted to the looped end 19^a of the bracket. The force of this spring tends to move the arm 26 rearwardly from the Fig. 3 to the Fig. 2 position. The upper end of the arm 26 extends through the slot 15 in the bracket and, when the parts are in the position indicated in Fig. 3, bears upwardly against the bottom of the slide so that the force of the spring 28 is at this time exerted upwardly on the slide, tending to hold it by friction in the retracted position. When, however, the operator desires to use the paper feed device it is merely necessary to grasp the finger piece 20 and move the slide rearward. This movement is continued until the forward edge 30 of the slide passes the upper end of the arm 26. When this occurs the arm 26 will bear against said forward edge instead of against the bottom of the slide and the force of the spring 28 will then be exerted endwise against the slide, tending to move it to the Fig. 2 position. After the slide arrives at this position the force of the spring is exerted thereon rearwardly of the machine to force and maintain the feed roller 23 against the platen or the paper thereon. The slide will remain in this position indefinitely or until it is moved by hand to the Fig. 3 position to retract the feed roller. The act of moving the slide to the Fig. 3 position automatically displaces the arm 26 to the Fig. 3 position, causing the end of the arm to bear upwardly against the bottom of the slide when the force of the spring is exerted laterally against the slide, or transversely of the direction of its movement, to hold it in the retracted position instead of being exerted endwise on the slide as in the Fig. 2 position.

It will be seen that I have provided a simple and efficient paper feeding device, where-in the effective force of the spring 28 is automatically changed to be applied in either of two directions at substantially right angles to each other by the mere act of moving the feed roller to or from effective position, and that it is unnecessary for the operator to make any movement of a part other than the mere movement of the slide to place the feed roller under spring pressure against the platen in effective position, or hold it under spring pressure away from the platen and in ineffective position.

It will be understood, moreover, that by my invention feed roller 23 may be moved from its operative Fig. 2 position a considerable distance away from the platen to the ineffective Fig. 3 position without stretching the spring 28 a corresponding distance. In fact, the spring is stretched less than one-half the distance the slide 16 is retracted to; or continues to be stretched only until the forward edge 30 of the slide reaches a point

just forward of the upper end of the arm 26, after which the slide and feed roller may be moved any desired distance without further affecting the spring. In other 5 words, the spring is progressively stretched or stressed during a portion only of the retraction of the slide. This relieves the spring from the exertion of an undue strain thereon which would weaken it and render 10 the retraction of the slide more difficult and makes it possible to utilize the force of the spring to more effectively press the feed roller 23 against the platen or the paper thereon; and it enables a much smaller 15 spring to be employed than would otherwise be necessary in a construction where it is desirable to move the roller as far away from the platen as in the present case.

Various changes may be made without de- 20 parting from my invention as it is defined in the accompanying claims.

What I claim as new and desire to secure by Letters Patent, is:—

1. In a typewriting or like machine, the 25 combination of a platen, a carrier mounted to slide towards and away from the platen, a paper feed device carried by said carrier, and a spring pressed pivoted member co-acting with said carrier and automatically 30 operative to hold it under spring pressure in either its projected position of use with said feed device bearing against the platen or in the retracted ineffective position depending on which position the carrier may 35 be shifted to by hand.

2. In a typewriting or like machine, the 40 combination of a platen, a carrier mounted to slide towards and away from the platen, a paper feed roller carried by said slide, a 45 spring, and means for directing the force of said spring either endwise on said carrier or transversely thereof as may be desired, thereby holding the carrier under spring pressure in either its effective or in- 50 effective position.

3. In a typewriting or like machine, the 55 combination of a platen, a carrier mounted to slide towards and away from the platen, a paper feed roller carried by said carrier, an arm pivoted on a relatively fixed part below said carrier and co-acting either with the bottom or with one end thereof depending on the position to which the carrier is moved relatively to said arm, and a spring 60 connected to said arm.

4. In a typewriting or like machine, the 65 combination of a carriage, a platen, a fixed support on the carriage, a slide mounted on said support for sliding movement towards and away from the platen, a paper feed device carried by said slide and movable there- 70 with into and out of position of use, and a spring pressed controlling member co-acting with the slide to exert a lateral pressure thereon when the slide is moved out of po- 75

sition of use and to exert an endwise pressure on the slide when the latter is in position of use.

5. In a typewriting or like machine, the combination of a carriage, a platen carried thereby, a fixed support on the carriage, a slide mounted on said support for movement fore and aft of the machine and into and out of position of use, a paper feed roller carried by said slide and movable by 75 the slide into and out of contact with the platen, and a spring pressed controlling member that automatically exerts a pressure on the slide either transversely of the path of its movement or in the direction of its path of movement depending on the position to which said slide is moved by hand.

6. In a typewriting or like machine, the combination of a carriage, a platen carried thereby, a sheet metal bracket detachably 80 fixed to the carriage, a sheet metal slide mounted for sliding movement only on said bracket into and out of position of use, a paper feed device carried by said slide at 85 one end thereof and moved by the slide into or out of contact with the platen depending on the direction in which the slide is shifted, a spring, and means for directing the force of said spring either endwise or laterally 90 against the slide depending on the position to which it is moved by hand, whereby the force of the spring is directed at one time to press the paper feed device against the platen and at another time to hold said de- 95 vice away from the platen.

7. In a typewriting or like machine, the combination of a carriage, a platen carried thereby, a bracket secured to the carriage and extending transversely of the platen, a carrier mounted on said bracket to slide 100 thereon towards and away from the platen, a paper feed device carried by said carrier and moved thereby into and out of contact with the platen or the paper thereon, a 105 spring, and means whereby the position of the carrier automatically directs the effective force of the spring either to force the feed device against the platen or to hold it away from the platen in its retracted position.

8. In a typewriting or like machine, the combination of a carriage, a platen carried thereby, a yoke-like sheet metal bracket secured at its ends to the carriage in front of the platen and extending fore-and-aft of the machine, a carrier mounted on said bracket to slide fore-and-aft of the machine, a paper feed device carried by said carrier and moved thereby into and out of contact with the platen or the paper thereon, a 120 spring, and means whereby the position of the carrier on the bracket directs the effective force of the spring either to slide the carrier towards and cause the feed device to bear against the platen or to hold 125

the slide in its retracted position with the feed device out of contact with the platen.

9. In a typewriting or like machine, the combination of a carriage, a platen carried thereby, a bracket carried by the carriage and having a slot therein, a paper feed device, a carrier therefor mounted to slide on said bracket, an arm beneath the bracket extending through said slot and adapted in one position of the carrier to bear against the same in a direction at substantial right angles to the direction of its sliding movement and in another position of the carrier to bear against it in the direction of its sliding movement, and a spring connected to said arm.

10. In a typewriting or like machine, the combination of a platen, a paper feed de-

vice, a sliding carrier therefor movable towards and away from the platen, a spring, and means whereby the force of said spring is exerted to move the carrier towards and maintain said feed device against the platen and whereby the spring is progressively stressed during a portion only of the retraction of said carrier, leaving said carrier free to be slid retractively a further distance without increasing or diminishing the tension of said spring.

Signed at Syracuse, in the county of 30
Onondaga and State of New York, this 11
day of October, A. D. 1922.
